UNITED STATES PATENT OFFICE.

PEREZ M. STEWART, OF NEW YORK, N. Y., ASSIGNOR TO GERTRUDE F. STEWART, OF NEW YORK, N. Y.

BUILDING CONSTRUCTION.

1,380,432.

Specification of Letters Patent. Patented June 7, 1921.

Application filed March 12, 1918. Serial No. 222,031.

To all whom it may concern:

Be it known that I, PEREZ M. STEWART, a citizen of the United States, and a resident of the borough of Manhattan, in the city, county, and State of New York, have invented an Improvement in Building Constructions, of which the following description, in connection with the accompanying drawings, is a specification, like characters 10 on the drawings representing like parts.

This invention relates to a reinforced building construction and more particularly to the roof and floors thereof, and has for its object to provide the building with a 15 practically monolithic roof or floor which is rigidly fastened to the purlins or beams of the framework of the building at a plurality of points distributed over the area of the monolithic structure, whereby a very 20 rigid attachment of the monolithic roof or floor against displacement is obtained.

To this end, the roof or floor is composed of a plurality of preformed slabs or sections of plastic material having metal reinforcements, and said slabs have their adjacent ends supported by the purlins or beams and spaced apart. Within the spaces between the ends of adjacent slabs are located means for connecting the metal reinforcements of adjacent slabs with the purlins or beams supporting the said slabs, and said spaces are then filled with plastic material which bonds with the slabs and practically forms a monolithic structure. 30

The invention further has for its object to provide extended bearing surfaces at each purlin or beam for the slabs to rest upon.

These and other features of this invention will be pointed out in the claims at the 40 end of this specification.

Figure 1 represents in section a sufficient portion of a reinforced building embodying the invention to enable it to be understood.

Fig. 2, a plan on a smaller scale of the 45 construction shown in Fig. 1.

Figs. 3 and 4, details of the connecting member preferred by me, and

Fig. 5, a section on a smaller scale of a 50 floor or roof embodying the invention.

To facilitate description I will hereinafter refer to the monolithic structure as a roof.

In accordance with this invention, the roof is composed of a plurality of individual preformed slabs or members *a* of normally plastic material, preferably gypsum or a 55 composition of gypsum, cement and a filler, such as wood shavings, in about the proportions of 65% of gypsum, 10% of Portland cement and 25% of wood shavings.

While I may prefer such a composition, 60 it is not desired to limit the invention in this respect.

Each of the slabs or members *a* is provided with a metal reinforcement, preferably consisting of a member or members 10 65 extended from one side or end of the slab near the upper surface thereof, down toward the bottom of said slab and then upwardly toward the opposite side or end and near to the upper surface of the slab, as 70 clearly shown in Figs. 1 and 5.

The reinforcing member 10 is preferably connected at its ends with transverse reinforcing members or rods 12 and is restrained from upward displacement by one 75 or more intermediate transverse members or rods 13 (see Fig. 5), which has a fixed position with relation to the bottom of the slab.

The slabs *a* are supported by the framework of the building and as herein represented by the roof purlins in the form of I-beams 14.

In order to obtain a wide or extended bearing or support for the ends of adjacent slabs *a*, the beams 14 support metal plates 85 or strips 15, shown in Fig. 2, as two in number but which may be of any desired number according to the length of the beam.

These plates extend beyond the sides of the beam for a substantial distance, so that 90 when the slabs *a* are laid on the beam, a substantial support is obtained for the slab with a relatively narrow beam.

The slabs *a* supported by the beam 14 are spaced apart and in this space is located a 95 member 16, preferably of sheet metal and which extends upward to near the top surfaces of the slabs *a*, so as to form a support for an adjusting and tying device, preferably in the form of a bolt 17, which is 100 passed through the metal clips 18, which are connected with the transverse reinforce-

ing members or rods 12 located at the adjacent ends of the slabs supported by the beam 14.

The bolt 17 is provided as shown with the nuts 20 which engage the clips 18, and by turning which the clips can be placed under tension, so that the metal reinforcements of adjacent slabs may be connected by a means also under tension, and substantially the same tension as that of the reinforcement of the slabs.

The tension members 17, 18, and the member 16 between adjacent slabs may be embedded in plastic material 22 which fills the space between the slabs and bonds to the latter so as to form a monolithic structure with a continuous metal reinforcement extended the length or width of the same structure.

20 The member 16 is secured to the beam 14, and in the present instance, the member 16 is provided at its lower end with arms 24, which are extended in opposite directions and bent around the head of the beam. The 25 member 16 and the arm 24 are shown separately in Fig. 3, and may be made from the flat blank shown in Fig. 4, by providing the latter with a cut or slit 25 to form the arms 24 and by providing the blank near its opposite end with a hole 26 for the passage of the bolt 17.

In the present instance, the bearing plate 15 is shown as provided with a slot 30 through which the member 16 is extended, but it is not desired to limit the invention to the particular arrangement of plate and member for securing said plate in fixed position on the beam.

By reference to Figs. 1 and 5, it will be 40 observed that the metal reinforcements for adjacent slabs are tied to or connected with the beam 14 which supports adjacent ends of said slabs, and when the roof or floor is completed by filling the spaces between the 45 ends of the slabs, a monolithic structure is obtained which is anchored to the beams or purlins at a plurality of points distributed over the area of the monolithic structure, and as a result the latter is firmly fastened 50 against displacement to the frame of the building, which is of especial importance in an inclined roof construction, as any tendency of the monolithic roof to slip is minimized.

55 It may be preferred to make the member 16 relatively rigid so as to not only act as a tie member for the metal reinforcements but also to obtain structural rigidity.

It is preferred to make the slabs largely 60 of gypsum as described, in order to save weight and thereby save in the cost of the metal framework of the building, and as these slabs have a low compressive value, the bearing or supporting plates are of 65 value, for with them wide or extended bear-

ings for the slabs are obtained at a minimum expense.

The invention has been described as embodied in the roof of a building, but it is not desired to limit it in this respect. 70

Claims:

1. In a building construction, in combination, a plurality of slabs provided with metal reinforcements and spaced apart at their adjacent ends, a beam supporting the adjacent ends of said slabs, metal clips attached to the metal reinforcements of said slabs and extended into the space between said slabs, a bolt adjustably connecting said clips, a supporting member for said bolt 80 secured to said beam, and a bearing plate for the adjacent ends of said slabs, said bearing plate being secured in fixed relation to said beam by said supporting member and extended beyond the sides of the beam and 85 under said slabs.

2. In a building construction, in combination, a plurality of slabs spaced apart at their adjacent ends and each provided with a longitudinal reinforcement extended from 90 near the upper surface of the slab at one end down toward the bottom near the center thereof and then up near the upper surface at the opposite end thereof, and having the ends of the reinforcements of adjacent slabs 95 extended into the space between said slabs below the upper surfaces of the latter, means located in the spaces between adjacent slabs for placing said longitudinal reinforcement under tension in the slabs independently of 100 the load to be supported by the slabs and for restraining said reinforcement against upward movement, means for connecting the longitudinal reinforcements of adjacent slabs below the upper surfaces thereof to 105 form a continuous tension member having substantially the same tension in adjacent slabs, and plastic material in the space between slabs for bonding them together to form a monolithic structure and for covering said connecting means.

3. In a building construction, in combination, a plurality of slabs spaced apart at their adjacent ends and provided with transverse reinforcing members located at their 115 ends near the upper surfaces thereof and with a transverse reinforcement located near the bottom of said slabs and with longitudinal reinforcements extended from the transverse reinforcement at one end of the 120 slab down to the bottom reinforcement and then up to the opposite end reinforcement, and adjustable means for connecting the upper transverse reinforcements of adjacent slabs.

4. In a building construction, in combination, a plurality of slabs provided with metal reinforcements and spaced apart, a metal support located below said slabs and provided with a flange, a bearing plate for the 130

- adjacent ends of said slabs supported by said flange and located between the upper face of the metal support and said slabs and extended beyond the sides of said support 5 and under said slabs, and a device secured to said support and coöperating with said bearing plate to secure the latter in fixed relation to said support.
5. In a building construction, in combination, a plurality of slabs spaced apart at 10 their adjacent ends and provided with transverse reinforcing members located at their ends near the upper surfaces thereof and with a transverse reinforcement located near 15 the bottom of said slabs and with longitudinal reinforcements extended from the transverse reinforcement at one end of the slab down to the bottom reinforcement and then up to the opposite end reinforcement, 20 and means for connecting the upper transverse reinforcements of adjacent slabs.
6. In a building construction, in combination, a plurality of slabs provided with metal 25 reinforcements and spaced apart, a metal support located below said slabs and provided with a flange, and a metal device coöperating with said metal support and having a member of substantial width extended upwardly above said metal support into 30 the space between the adjacent ends of the slabs resting on said flange.
7. In a building construction, in combination, a plurality of slabs spaced apart and provided with longitudinal metal reinforce- 35 ments connected together in the space between said slabs to form a continuous reinforcement, a metal support for the adjacent ends of said slabs, and a device coöperating with said metal support below said slabs 40 to have a fixed relation thereto and having a member extended into the space between the slabs and coöperating with the metal reinforcement in said space to tie the reinforcement to the metal support for the slabs.
- 45 8. In a building construction, in combination, a plurality of slabs spaced apart, supports upon which the ends of adjacent slabs rest, plastic material in the spaces between said slabs and bonding the slabs together to 50 form a monolithic structure, a metal reinforcement for each slab extended longitudinally thereof, means extended across the spaces between adjacent slabs for connecting the longitudinal reinforcement of each slab with that of the next adjacent slab to 55 form a continuous longitudinal reinforcement for the monolithic structure, and means located in the spaces between adjacent slabs and embedded in the plastic ma- 60 terial therein and extended at an angle to said reinforcement for connecting the longitudinal reinforcement of the monolithic structure to said supports to anchor said monolithic structure to said support at va- 65 rious points throughout its area.
9. In a building construction, in combination, a plurality of slabs spaced apart and provided with longitudinal metal reinforce- 70 ments connected together in the space between said slabs to form a continuous reinforcement, a metal support for the adjacent ends of said slabs, and a device coöperating with said metal support below said slabs to have a fixed relation thereto and having a member extended into the space between the 75 slabs.
10. In a building construction, in combination, a plurality of preformed slabs of 80 plastic material spaced apart, supports upon which the ends of adjacent slabs rest, plastic material above said supports in the spaces between said slabs and bonding the slabs together to form a monolithic structure, a metal reinforcement for said monolithic structure comprising a continuous longitudi- 85 nally extended reinforcement, and a transverse metal reinforcement, said longitudinal reinforcement being composed of metal members individual to said preformed slabs and connected together in the spaces be- 90 tween adjacent slabs below the upper surfaces of the latter and above said supports, and said transverse reinforcement being composed of end members and an intermediate member individual to said preformed 95 slabs with the end members located near the upper surfaces of said slabs and coöperating with the longitudinal reinforcement thereof to restrain the latter against downward movement in said slabs, and with the intermediate members located near the bottom of said slabs and coöperating with the longitudinal reinforcement to restrain the latter against upward movement in said slabs. 100
11. In a building construction, in combination, a plurality of slabs spaced apart and provided with longitudinal metal reinforce- 105 ments connected together in the space between said slabs and below the upper surfaces thereof to form a continuous reinforcement, transverse reinforcing members located near the adjacent ends of the slabs and near the upper surfaces thereof and which support the longitudinal metal reinforce- 110 ments against downward movement, and a transverse reinforcing member located near the bottom of each of said slabs between the end reinforcing members there- 115 of and coöperating with the latter and the longitudinal reinforcement to restrain the longitudinal reinforcement against upward movement and to place the latter in adjacent slabs under substantially the same tension independently of the load to be sup- 120 ported by the slabs and supports located be- 125 low said slabs and upon which the adjacent ends of said slabs rest.
12. In a building construction, in combination, a plurality of slabs spaced apart at 130

their adjacent ends and provided with transverse reinforcing members located at their ends near the upper surfaces thereof and with a transverse reinforcement located near 5 the bottom of said slabs and with longitudinal reinforcements supported by the transverse reinforcement at one end of the slab and extended down to the bottom reinforcement and then up to the opposite end rein-

forcement and supported by the latter, and 10 means for connecting the longitudinal reinforcements of adjacent slabs within the space between adjacent slabs and below the upper surfaces of the latter.

In testimony whereof, I have signed my 15 name to this specification.

PEREZ M. STEWART.
